US0D1060385S

(12) **United States Design Patent** (10) **Patent No.:** **US D1,060,385 S**
(45) **Date of Patent:** **** Feb. 4, 2025**

(54) **DISPLAY SCREEN OR PORTION THEREOF
WITH GRAPHICAL USER INTERFACE**

(71) Applicant: **Google LLC**, Mountain View, CA (US)

(72) Inventors: **Jennifer Veneranda Cordova**, San Mateo, CA (US); **Alexander John Medearis**, San Francisco, CA (US); **Zhujun Yao**, San Carlos, CA (US); **Vikram Padmakar Bapat**, San Francisco, CA (US)

(73) Assignee: **GOOGLE LLC**, Mountain View, CA (US)

(**) Term: **15 Years**

(21) Appl. No.: **29/876,712**

(22) Filed: **May 26, 2023**

(57) **CLAIM**

The ornamental design for a display screen or portion thereof with graphical user interface, as shown and described.

DESCRIPTION

The sole FIGURE is a front view of an electronic device having a display screen or portion thereof with a graphical user interface applied to the display screen or portion thereof of a display screen or portion thereof with icon, showing the new design.

The evenly spaced broken lines in the FIGURE show the electronic device and portions of the display screen or portion thereof with graphical user interface, and form no part of the claimed design. The dot-dash broken lines in the FIGURE show a display screen or portion thereof and form no part of the claimed design.

1 Claim, 1 Drawing Sheet
